(57) **CLAIM**

The ornamental design for a hand-held cutting tool as shown and described.

DESCRIPTION

FIG. 1 is a perspective view of a hand-held cutting tool showing our new design;

FIG. 2 is a top plan view of the hand-held cutting tool of FIG. 1;

FIG. 3 is a bottom plan view of the hand-held cutting tool of FIG. 1;

FIG. 4 is a right side elevational view of the hand-held cutting tool of FIG. 1;

FIG. 5 is a left side elevational view of the hand-held cutting tool of FIG. 1;

FIG. 6 is a front elevational view of the hand-held cutting tool of FIG. 1; and,

FIG. 7 is a rear elevational view of the hand-held cutting tool of FIG. 1.

The broken lines depict portions of the hand-held cutting tool in which the design is embodied that are not considered part of the claimed design.
